UNITED STATES PATENT OFFICE.

ORLIE F. LIPPINCOTT, OF KENESAW, NEBRASKA.

STARTING DEVICE FOR EXPLOSIVE-ENGINES.

1,172,893.

Specification of Letters Patent.

Patented Feb. 22, 1916.

Application filed June 3, 1915. Serial No. 32,005.

To all whom it may concern:

Be it known that I, ORLIE F. LIPPINCOTT, a citizen of the United States, residing at Kenesaw, in the county of Adams and State 5 of Nebraska, have invented certain new and useful Improvements in Starting Devices for Explosive-Engines; and I do hereby declare the following to be a full, clear, and exact description of the invention, such as will 10 enable others skilled in the art to which it appertains to make and use the same.

My invention relates to new and useful improvements in starting devices for explosive engines, and my object is to provide 15 in conjunction with a sparking plug a jacket for carrying the sparking plug and a chamber for carrying the explosive substances.

A further object is to provide a sleeve in connection with the cylinder of the engine 20 into which the sparking plug and parts connected thereto is to be introduced. And a further object is to provide a quick detachable locking means for securing the sparking plug in the sleeve.

25 Other objects and advantages will be hereinafter set forth and more particularly pointed out in the accompanying specification.

In the accompanying drawings which are 30 made a part of this application, Figure 1 is an elevation of a portion of a cylinder showing my improved device attached thereto, and Fig. 2 is a vertical sectional view thereof, showing the spark plug in full lines.

35 Referring to the drawings in which similar reference numerals designate corresponding parts throughout the several views, 1 indicates the cylinder of a combustion engine which may be constructed in the usual 40 or any preferred manner and having an opening 2 therein which is interiorly threaded to receive the threaded end of a sleeve 3. Adapted to be introduced into the outer end of the sleeve 3 is a cylindrical jacket 4, the 45 outer end of which is provided with a collar 5, the inner edge of said collar forming a shoulder to abut against the end of the sleeve 3, the interior of the collar being threaded to receive a locking nut 6 which serves to hold 50 the spark plug 7 properly seated in the jacket.

In order to securely lock the jacket 4 within the end of the sleeve 3 and at the same time render the same quickly detachable 55 therefrom, a lug 8 is provided on the outer face of the jacket 4, said lug coacting with a

bayonet shape slot 9 extending inwardly from the outer end of the sleeve 3 so that when the lug is entered in the open end of the slot and moved inwardly its full distance and then rotated to enter the same in the angular portion of the slot, the jacket and parts carried thereby will be securely held in engagement with the sleeve.

In order to obviate any possibility of the 60 jacket rotating within the sleeve to register the lug with the open portion of the slot 9, the lug is provided with a recess 10 into which is introduced a locking latch 11, a spring 12 being entered in the recess above 65 the latch to normally hold the same in lowered position. The projecting end of the latch is adapted to engage a notch 13 in the sleeve 3 and when so engaged prevents rotation of the jacket 4. In order to readily remove the latch from engagement with the 70 notch, a pin 14 is attached to the latch 11 and extended through a slot 15 in the lug, the outer end of the pin being in position to be readily grasped to raise the latch.

75 The spark plug 7 may be of any preferred make and extends into the jacket to a point adjacent the inner end thereof, said plug having a pin 16 which is adapted to co-operate with a pin 17 carried by the 80 end of the jacket 4, said pins co-operating to produce a spark when an electric current is introduced therethrough.

Surrounding the reduced end of the jacket 4 is a tube 18, which tube extends beyond the inner end of the jacket and to a point adjacent the inner end of the sleeve 3, said tube forming a chamber for the reception of any suitable form of explosive material 19, said explosive material also 90 being packed around the sparking pins 16 and 17 so that when the spark is created at the gap between the two pins, the explosive material will be exploded.

95 This device is designed for the purpose of 100 employing the force of the explosive material to start the engine, thus obviating the possibility of injury to any one attempting to start the engine manually, as it is but necessary with this device, to properly 105 set the piston within the cylinder and then discharge the explosive material.

In operation, the jacket and parts carried thereby are removed from the sleeve 3 and a proper charge of explosive material 110 placed within the tube 18 and packed around the sparking pins 16 and 17, when the jacket

is reentered into the sleeve and interlocked therewith through the medium of the lug and bayonet shape slot previously described. The piston is then properly set within the 5 cylinder and a switch 20, or other suitable device, operated to close the circuit between the battery wires 21 and 22 which will result in directing a current through the 10 sparking pins 16 and 17 and causing a spark in the gap between said pins, such sparks igniting the explosive material and causing the same to explode, the force of the explosion within the cylinder causing the piston thus operated to start the engine. 15 Instead of using the interlocking means shown between the sleeve and jacket, any other suitable means may be employed as may be desired.

This device can be very cheaply constructed and readily applied to use in connection with any form of internal combustion engine and as many charges of the explosive material as may be desired, may be entered into the tube and fired through 25 the medium of the sparking arrangement.

Having thus fully described my invention what I claim as new and desire to secure by Letters Patent of the United States is:—

1. A starting device for engines comprising the combination with a cylinder having an opening therein, and a sleeve extending from said opening, of a jacket, a tube connected to the inner end of the jacket adapted to contain an explosive powder, a sparking 35 arrangement carried by the jacket comprising a pair of pins connected in circuit with the positive and negative poles of an electric generator, a locking nut adapted to secure the sparking arrangement to the jacket, 40 a lug adapted to interlock with a slot formed in said sleeve and a spring actuated latch carried by the lug adapted to interlock with the sleeve and hold the jacket against rotation.

45 2. A starting device for engines comprising

the combination with a cylinder having a hollow sleeve projecting therefrom, said sleeve having a slot at its outer end and a notch coöperating with the slot, of a jacket having an enlarged collar at its outer end, 50 a sparking device carried by the jacket comprising a pair of pins connected in circuit with the positive and negative poles of an electric generator, means to lock the 55 sparking device to the jacket, a tube at the inner end of the jacket adapted to contain an explosive powder, a lug on the jacket adapted to coöperate with the slot in the sleeve and interlock therewith, a spring 60 pressed latch slidably mounted in said lug adapted to engage the notch in the sleeve and hold the jacket against rotation and an operated pin carried by the latch.

3. A starting device for engines, comprising the combination with a cylinder and 65 a hollow sleeve connected therewith, said sleeve having a bayonet slot in its outer extremity, of a jacket, a tube carried by the jacket adapted to contain an explosive powder, a sparking arrangement carried by the 70 jacket comprising a pair of pins connected in circuit with the positive and negative poles of an electric generator, a lug integral with the jacket and adapted to enter and interlock with said slot, a latch slidably 75 mounted in the lug and adapted to interlock the parts of the sleeve and hold the jacket against rotation, means to normally hold the latch in extended position, and means whereby the latch may be operated to release the same from engagement with the 80 sleeve.

In testimony whereof I have signed my name to this specification in the presence of two subscribing witnesses.

ORLIE F. LIPPINCOTT.
